JOSEPH J. SMITH, OF PHILADELPHIA, PENNSYLVANIA

DISPENSING DEVICE

Application filed July 13, 1931. Serial No. 550,416.

This invention relates to a dispensing apparatus, and has for an object to provide improved means for dispensing the contents of collapsible tubes.

A further object of the invention is to provide a structure adapted to collapse a collapsible tube progressively, and includes improved means for conducting the exuded material to the point of use.

20 A further object of the invention is to provide a structure embodying adjacently journaled rollers between which a collapsible tube is successively wound, with improved means making contact with the nipple end 25 of the collapsible tube following such nipple and end in the progressive rolling and conducting of the exuded material to the point of use.

The invention, therefore, comprises a structure upon which is journaled adjacent rollers, with means for rotating the rollers, such rollers being properly proportioned to receive therebetween a collapsible tube, with an upright having a follower movable thereon carrying a cap covering over the nipple or other end section of the tube, with a conduit for conducting the material, and a closure for the conduit.

The invention is directed to other objects, and possesses other features of novelty and advantage, some of which, together with the foregoing, will be hereinafter more fully set forth.

In the drawings:

35 Figure 1 is a view of the device in side elevation, parts being broken away,

Figure 2 is a view of the device in front elevation, parts being broken away,

40 Figure 3 is a view in front elevation with a part broken away of the winding drum for actuating the follower,

Figure 4 is a sectional view taken on line 4-4 of Figure 1, and showing the follower, guide and supporting member,

45 Figures 5 and 6 are, respectively, a section and a side elevation of two embodiments of the delivery tube and closure,

50 Figure 7 is a view partly in side elevation and partly in section of the ratchet mechanism for actuating the rollers,

Figure 8 is a sectional view, taken on line 8-8 of Figure 1, showing the cap covering the end of the nipple,

Figure 9 is a view similar to Figure 8, showing a square delivery end of the tube, 55

Figure 10 is a view in side elevation of a modified type of roller operating structure.

Like characters of reference indicate corresponding parts throughout the several 60 views.

The improved dispensing apparatus, which forms the subject matter of this application, is adapted for cooperation with collapsible tubes of various kinds, one of which is represented at 15 in the drawings. Such tubes normally contain creamy or pasty materials which are exuded through the nipple 16 at the end by collapsing the tube at the opposite end, or intermediate the ends. The present 70 structure comprises a plate 17, which may be secured to a wall, or other supporting structure, with side brackets or plates 18 extending therefrom, such plates or brackets being connected at their ends opposite the plate 17 75 by a cross bar 19.

The side brackets 18 serve for journaling the shafts 20 and 21, carrying rollers 22 and 23. These rollers 22 and 23 are so placed, that the lower end of the tube 15 may be inserted therebetween, and by the rotation of the rollers, wind the tube through to the position 15'.

For winding the rollers, a lever or key 24 is mounted upon the shaft 20 by means of a 85 sleeve 25 which is provided upon the end with ratchet teeth 26. A ratchet collar 27 is rigidly secured to the shaft 20. The sleeve 25 contains a spring 28 which operates at one end against the end of the sleeve, and at the opposite end against the pin 29 which is inserted through the shaft 20 so that the sleeve is normally held away from the bracket and the ratchet teeth disengaged. When it is to be operated, the key 24 and sleeve 25 are pushed inwardly against the tension of the spring 28 until the ratchet teeth interengage. This arrangement prevents the rotation of the rollers in a direction to unwind the section 15'. 95 100

Upon the back plate, a slotted tubular upright 30 is erected, with a follower 31 slidable therein. An arm 32 extends outwardly through the slot and is provided with a collar 33. The collar 33 engages about the discharge tube 34. Said discharge tube is provided upon the underside of the arm 32, with a tapered cap 35 which fits over the nipple 16, and the tube is also bent at right angles, as shown more particularly at Figures 1, 5 and 6, and is provided at the end with a closure. As shown at Figures 1 and 5, this closure comprises a weighted member 36, hinged at 37 so that when pressure is released, the weight 15 will close the closure to protect the contents of the tube. Instead of employing a weight, a cover 36', as shown at Figure 6, is hinged at 37', and a spring 38 is employed for holding the closure 36' yieldingly in closed position.

The follower 31 is also provided with a cord or cable 39 extending downwardly through the tubular upright 30, and wound about a drum 40, journaled to the back plate 25 upon the journal 41. This winding drum 17 is provided with a spring 42, tending to at all times exert stress upon the cable 39 so that the cap 35 is at all times held firmly in engagement with the nipple 16.

Instead of forming the cap 35 circular in cross section, as shown at Figure 8, and indicated at Figure 1, it may assume other forms for co-action with delivery ends of collapsible tubes which assume other than a circular 35 form. Merely as an example of this, there has been shown at Figure 9, a delivery part 16' square in cross section, and the cap 35' likewise square in cross section.

While such square formation is shown, it is 40 merely shown as an illustration of a departure from the circular, and is intended to include any and all formations other than circular.

Instead of employing the key 24 and 45 ratchet mechanism associated therewith for the actuation of the rollers, the shaft 20, will, in the modification shown in Figure 10, be provided with a pinion 43. A rack 44 will engage this pinion, and is provided with a slot 50 45 sliding upon a fixed pin 46. A knob or other convenient means for manipulation is provided at the outer end of the rack 44 as shown at 47, and a spring 48 is connected with the opposite end.

In operation, of the type shown at Figure 55 1, the cap 35 will be raised by lifting the arm 32, raising thereby the follower 31 and unwinding the cable 39 against the tension of the spring 42. When sufficient clearance has 60 been provided, the collapsible tube will be introduced by inserting the bottom folded edge between the rollers 22 and 23, and the cap 35 then allowed to assume its position upon the nipple 16 through the tension of 65 the spring 42, cable 39 and follower 31. The

key 24 will be manipulated in the only direction it will operate until the contents of the tube have exuded from the nipple into the cap through the delivery tube 34 and raised the closure 36 or 36'. Upon the release of the tension upon the key, the closure 36 or 36' will close.

Instead, however, of employing the key as above outlined, the type shown at Figure 10 may be employed by pushing inwardly on 75 the knob 47, in the direction indicated by the arrow, which will rotate the pinion 43 and therewith, the roller 22 to which it is attached. The requisite amount of rotation having been applied, pressure upon the knob 47 is released. By reason of the position of attachment of the spring 48 with the rack 44, it will lift the rack 44 from engagement with the pinion 43 and retract it to the position shown at Figure 10. In this position, the parts are arranged by a repetition of the action.

Of course, the dispensing device, herein illustrated, may be modified in various ways without departing from the invention herein set forth and hereinafter claimed.

The invention is hereby claimed as follows:

1. A dispensing device for collapsible tubes comprising a frame, a pair of rollers fixedly journaled upon the frame adapted to collapse a tube, a cap carried by the frame adapted to close the end of the tube opposite the collapsible end, a delivery tube carried by the cap, and means to hold the cap yieldingly in engagement with the tube as it is progressively collapsed by the rollers.

2. A dispensing device for collapsible tubes comprising a pair of fixedly journaled adjacent rollers, an upright fixed relative to the rollers, a follower movable along the upright, means to exert stress upon the follower, a cap carried by the follower, a discharge tube carried by the cap, and a closure for the discharge tube.

3. A dispensing device for collapsible tubes comprising a pair of fixedly journaled adjacent rollers, means to actuate the rollers in one direction only, an upright fixed relative to the rollers, a follower carried by the upright and slidable relative thereto, a tapered cap carried by the follower, a delivery tube carried by the cap, and a closure for the delivery tube.

4. A dispensing device for collapsible tubes comprising a pair of fixedly journaled adjacent rollers, means to rotate the rollers in one direction only, with a step-by-step action, an upright fixed relative to the rollers, a follower slidable relative to the upright, means to exert yielding tension upon the follower, a tapered cap carried by the follower, a delivery tube carried by the cap, and a closure for the delivery tube.

5. A dispensing device for collapsible tubes comprising a pair of fixedly journaled adj-

cent rollers, means to apply manual stress to rotate the rollers in one direction only, a tubular upright fixed relative to the rollers, a follower slidable within the tubular upright, 5 a tapered cap carried by the follower, a delivery tube carried by the cap, and a closure for the delivery tube.

6. A dispensing device for collapsible tubes comprising a pair of fixedly journaled adjacent rollers, means to apply manual stress to 10 rotate the rollers in one direction only, a slotted tubular upright fixed relative to the rollers, a follower slidable in the upright, means to apply yielding tension to the follower, an arm carried by the follower extending 15 through the slot, a cap carried by the arm, a delivery tube carried by the cap, and a closure for the delivery tube.

7. A dispensing device for collapsible tubes 20 comprising a pair of fixedly journaled rollers, a slotted upright fixed relative to the rollers, a follower mounted to slide in the upright, a spring actuated winding drum journaled relative to the rollers, a cable wound 25 upon said drum and connected with the follower, an arm carried by the follower extended through the slot, a tapered cap carried by the arm, a delivery tube carried by the cap, and a closure for the tube.

30 In testimony whereof I have signed my name to this specification.

JOSEPH J. SMITH.
